UNITED STATES PATENT OFFICE.

HENRY SAWYER, OF CHELSEA, MASSACHUSETTS.

DESIGN FOR BOTTLE.

Specification forming part of Design No. **6,489**, dated March 4, 1873.

To all whom it may concern:

Be it known that I, HENRY SAWYER, of Chelsea, in the county of Suffolk and State of Massachusetts, have invented a new ornamental Configuration or Design for a Bottle; and do hereby declare the same to be fully described in the following specification and represented in the accompanying drawing, of which—

Figure 1 denotes a front elevation. Fig. 2 is a side elevation, Fig. 3 a transverse section, and Fig. 4 a bottom view, of bottle having the external configuration or form constituting such design.

The bottle, at its base or bottom *a*, is rectangular or square, with rounded corners. From the bottom *a* upward the body *A* tapers on two opposite sides, *b b*, increasing in width to about the middle of the body, the other two or front and rear sides *c c* being parallel, or about so,

and each being formed with a circular recess or panel, *d*, having its boundary or border *e* in relief. From the tops of the two borders *e*, and from the upper parts of the straight sides *b b*, the neck *B* springs, and is curved upward, and terminates in a cylindrical or slightly-conical head, *f*, in manner as shown. From the corners of the bottom narrow fillets *g* extend upward in relief at the junctures of the sides, and are covered or arched across the base of the neck, in manner as shown.

I claim—

The ornamental design or configuration for a bottle, substantially as specified and represented.

HENRY SAWYER.
